UNITED STATES PATENT OFFICE.

RALPH WILSON JONES, OF LINCOLN, NEBRASKA, ASSIGNOR TO JONES MANUFACTURING CO., OF CHICAGO, ILLINOIS, A CORPORATION.

STAMP-HANDLING DEVICE.

1,003,267.

Specification of Letters Patent. Patented Sept. 12, 1911.

Application filed March 17, 1910. Serial No. 549,820.

To all whom it may concern:

Be it known that I, RALPH W. JONES, a citizen of the United States, and a resident of Lincoln, in the county of Lancaster and 5 State of Nebraska, have invented a new and Improved Stamp-Handling Device, of which the following is a full, clear, and exact description.

This invention relates to devices for holding and manipulating postage and other adhesive stamps, and has reference more particularly to a device of this class, comprising a casing constituting a magazine for the stamps, a guide member associated with 15 the magazine and adapted to have the stamps passed along it manually, from the casing to the point of application of the stamps, and a moistening device for wetting the adhesive of the stamps before they are 20 applied.

The object of the invention is to provide a simple, strong and durable holding and manipulating device, which is compact in form and inexpensive to manufacture, in 25 which a comparatively large number of adhesive stamps such as postage stamps, can be contained, and which permits the stamps to be applied to letters or other articles, rapidly, and without the necessity of using 30 a separate moistening device, the stamps being provided with the necessary water for wetting the adhesive thereof before they leave the device.

The invention consists in the construction 35 and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a side elevation of an embodiment of my invention, showing a part 45 broken away and a part in longitudinal section; Fig. 2 is a transverse section of the guide member and the moisture receptacle of the device; Fig. 3 is a plan view of the invention; Fig. 4 is a side elevation of a modified form of the device; Fig. 5 is a 50 transverse section of the modified form; Fig. 6 is a plan view of the modified form of the device; Fig. 7 is a perspective view showing the manner of manipulating the

device; Fig. 8 is a side elevation of another 55 modified form of the device; Fig. 9 is a plan view of the last-mentioned modified form; Fig. 10 is an enlarged longitudinal section of the form shown in Figs. 8 and 9, with a part broken away; and Fig. 11 is a transverse section on the line 11—11 of Fig. 10.

Before proceeding to a more detailed explanation of my invention, it should be clearly understood that while the device is particularly useful in connection with 65 postage stamps, it can also be advantageously employed for holding and manipulating other like stamps, which are frangibly connected in series, and can be arranged in strips. The casing constituting the 70 stamp magazine may be of any suitable size, so that a comparatively large number of stamps can be held in the casing, and so that the stamps need not be replenished except at considerable intervals of time. The guide 75 member is preferably of such a length that it can be conveniently grasped in the hand, as is shown in Fig. 7, leaving the thumb free to advance the stamps along the guide member to the point of application at the end of 80 the same. Certain of the details of construction form no part of the invention, and can be varied in accordance with individual preference and special conditions, without departing from the underlying spirit of the 85 invention.

Referring more particularly to the drawings, I provide a casing 10, which is of substantially cylindrical form, and is fashioned from sheet metal or other suitable material. 90 It has associated therewith a hinged cover 11 forming one of the sides of the casing, and provided with laterally disposed flanges which engage at the walls of the casing and assist in securing the cover in a closed position. The casing is extended to form a tapered outlet 12. It has a post or spindle 13 near the center, about which a roll of stamps 14 can be arranged.

A guide member 15 is associated with the 100 casing, at the outlet thereof, and may be formed, for example, by an extension of one wall of the casing. It has at the opposite longitudinal edges, inwardly disposed flanges 16 under which the stamps slide, and 105 which serve to hold the stamps movably in position while they are being advanced along the guide member.

A reservoir 17 is located under the guide member and is permanently secured thereto. It has a capped inlet 18 through which water can be introduced, and is filled with suitable absorbent material 19, such as cotton wool, which distributes the moisture. The guide member has perforations 20, and adjacent thereto, slots 21 through which communication with the interior of the reservoir is effected; so that moisture from the latter can pass to the stamps as the same move over the perforations and the slots, in traveling along the guide member. The openings through which the moisture can escape from the reservoir to the stamps may be of any other suitable form.

In Figs. 4, 5 and 6, I have shown a modified form of the device, in which is employed a casing 22, having a cover 23 and an outlet 24. The guide member 25 is formed by an extension of one of the casing walls, and has arranged over it a flange 26, formed by an extension of the other casing wall. The flange 26 projects entirely over the guide-member, and has a slot 27 which permits the thumb to be utilized in advancing the stamps along the guide member, under the flange. The guide member has perforations 28 and slots 29, through which moisture can escape from the reservoir 30 under the guide member.

In manipulating the device, it is grasped in the hand, by means of the guide member and the reservoir, so that the exposed part of the guide member is uppermost, to permit the thumb to be moved along it. In this way, the stamps are advanced along the guide member and are projected from the end of the same, moistened and ready to be applied to an envelop or other article. The fingers of the other hand may be used to press the stamp upon the envelop, and a movement of the device permits the stamp to be torn loose from the rest of the strip, so that the next successive stamp can be projected beyond the end of the guide member, and can be applied to the next article.

In Figs. 8, 9, 10 and 11, I have shown a further modified form of the device, in which the casing 31 is likewise of substantially cylindrical form, and is fashioned from material similar to that of the other forms. It has associated therewith, a hinged cover 32 similar to the cover 11, which forms one of the sides of the casing and is provided with laterally disposed flanges engaging at the walls of the casing, to assist in securing the cover in a closed position. The casing is extended to form a tapered outlet 33, and has the walls thereof extended to form the guide member 34 and the edge flanges 35 thereof. The latter are spaced from the surface of the guide member proper, and are inwardly disposed as shown most clearly in Fig. 11. The flange 35 adjacent to the cover

32 has a cutaway part 36 which facilitates the introduction of the stamps 37 into the guide member when the roll is being placed in the casing. Underneath the guide member 34 is mounted a reservoir carrier 38, which is open at the end adjacent to the free end of the guide member, and which extends to the casing 31. It serves to stiffen the guide member, and to render the entire device stronger. The reservoir 39 is slidably mounted in the carrier and has an upwardly inclined or beveled end 40 adapted to project at the open end of the guide member. The reservoir contains absorbent material 41 with which the stamps 37 come in contact when passing from the end of the guide member so that they can be moistened, as is shown most clearly in Fig. 10. The guide member 34 may also be provided with openings 42 near the free end, through which moisture can escape to the gummed surface of the stamps. The reservoir is removable and can be slid out at the open end of the carrier.

Having thus described my invention, I claim as new, and desire to secure by Letters Patent:

1. A device of the class described, comprising a casing having a cover, and an outlet, said casing having a wall extended beyond said outlet and forming a guide member adapted to receive stamps from said casing, whereby the stamps can be moved along said guide member, said guide member having a flange extending over it, and a reservoir carried by said guide member, said guide member having openings near the end thereof, communicating with said reservoir.

2. A device of the class described, comprising a casing, constituting a magazine for stamps, a guide member associated with said magazine and adapted to have stamps passed along it from the casing to the point of application of the stamps, a carrier associated with said guide member, and a reservoir movably held by said carrier, said reservoir projecting at the end of said carrier and having absorbent material for supplying moisture at the projecting end of said reservoir to the stamps as they are advanced from said guide member.

3. A device of the class described, comprising a casing having a cover and an outlet, said casing having a wall extended beyond said outlet and forming a guide member adapted to receive stamps from said casing, said casing having another wall extended beyond said outlet and forming retaining flanges for said guide member, and a reservoir carried by said guide member to supply moisture to stamps passing along said guide member, one of said flanges being cut away adjacent to said outlet of said casing.

4. A device of the class described, com-

prising a casing constituting a magazine for stamps, a guide member associated with said casing and partly exposed, whereby the stamps can be caused to move along said 5 guide member from said casing, and a reservoir adjacent to said guide member and having an open end at the end of said guide member, provided with an upwardly disposed lip, projecting beyond the said guide 10 member, and absorbent material in said

reservoir and projecting beyond said guide member at said open end of said reservoir.

In testimony whereof I have signed my name to this specification in the presence of two subscribing witnesses.

RALPH WILSON JONES.
